UNITED STATES PATENT OFFICE.

SAMUEL TOOMEY, OF CANAL DOVER, OHIO.

THILL FOR SULKIES.

SPECIFICATION forming part of Letters Patent No. 403,079, dated May 7, 1889.

Application filed March 11, 1889. Serial No. 302,841. (No model.)

To all whom it may concern:

Be it known that I, SAMUEL TOOMEY, a citizen of the United States, and a resident of Canal Dover, county of Tuscarawas, State of Ohio, have invented a new and useful Improvement in Thills for Sulkies, of which the following is a full, clear, and exact description, reference being had to the accompanying drawings, making part of this specification.

10 My invention relates to improvements in sulkies, particularly to the class used for speeding horses; and it consists in a peculiar construction of thill by which a minimum in size and weight is reached and yet retain the necessary amount of strength, as hereinafter described, and set forth in the claim.

Figure 1 of the accompanying drawings, is a view in perspective of a sulky, illustrating my invention. Fig. 2 is a plan view of thill; 20 and Fig. 3 is a view of the cross-section, as from x to x , full size.

In sulkies for speeding horses it is essential to the best results that the thills should be absolutely unyielding at those points under 25 the feet of the driver, and at the same time that the thills should be as light as possible consistent with such rigidity. To this end I construct the thill of the form shown in the cross-section, Fig. 3, taken on the lines x in 30 Figs. 1 and 2, which I call an irregular oval, oblique, the longest diameter being oblique and on a line as from B to C. The lower outside portion or bulge serves to make the thill unyielding to the outward and downward

pressure of the driver's feet, as well as to prevent the draft and jar on the axle-spindles; and to overcome any tendency to yield downward I form a bulge inwardly below the horizontal axis and outwardly on the opposite side above the horizontal axis. These bulges are shown 40 connected by the line D E in the drawing Fig. 3, the line G H showing the general direction of the downward pressure.

Between the points B, C, D, and E the contour of the thill is arched just enough to retain the stiffening tendency of the curved form over the straight, and at the same time is sufficiently flattened to get rid, as far as possible, of unnecessary material.

The result as found in practice is a thill of 50 very great rigidity and of unusual lightness.

Having thus fully described the nature and object of my invention, what I claim as new, and desire to secure by Letters Patent, is—

The herein-described thill, irregular in 55 cross-section, the diameter of the cross-section being greatest in the oblique direction from B to C, and having bulges on opposite sides, one above and one below the horizontal axis, substantially as set forth.

In testimony whereof I have hereunto set my hand this 25th day of February, A. D. 1889.

SAMUEL TOOMEY.
